UNITED STATES PATENT OFFICE.

JEREMIAH A. SHOWALTER, OF SAVANNAH, GEORGIA.

WELL-DRILLING MACHINE.

Application filed April 14, 1928. Serial No. 270,001.

My invention relates to improvements in cable well drilling machines in which the borings are removed from the well during the progress of the work and has for a principal object to provide a new and novel means for removing the borings without drawing the tools from the well so that the drilling may proceed continuously and without interruption.

10 A further object of the invention is to provide a hydraulic drilling apparatus having means connected therewith for forcing a supply of water through the drilling tool, said drilling tool being further adapted for use 15 in removing water from the well, when desired, during the drilling operation.

A still further object is to provide a drilling machine of this character of simple and practical construction, which is strong and durable, efficient and reliable in performance, relatively inexpensive to manufacture and maintain in operation and otherwise well adapted to the purposes for which the same is intended.

25 Other objects and advantages reside in the special construction and combination of the various elements comprising the invention, reference being had to the accompanying drawings forming a part hereof, wherein:

30 Figure 1 is a side elevational view of the apparatus,

Figure 2 is a top plan view with the borings removed,

35 Figure 3 is a fragmentary end elevational view of the hose drum, with parts shown in section showing the manner of feeding the water to the hose through the shaft of the drum,

40 Figure 4 is an elevational view of the drilling tool in assembled position.

Figure 5 is a transverse sectional view therethrough taken substantially along a line 5—5 of Figure 4, and

45 Figure 6 is a longitudinal sectional view through one of the connections for the tool and illustrating the position of the jetting valve arranged therein and used in connection with the tool when removing water from the well.

50 Referring now to the drawings in detail, the invention comprises a wheeled truck comprising a body or platform 5 mounted on wheels 6, one end of the platform providing a support for a vertically extending derrick 7 having a brace 8 connected at its upper end and extending to post 9 carried at the opposite

end of the platform serving to support the derrick in vertically extended position. Upon the post 9 is pivotally mounted a walking beam 10 having its free end extending in a direction toward the derrick and operated through a connecting rod 11 eccentrically connected with a gear wheel 12 journaled for rotation on the frame or platform 5.

The gear wheel 12 is operated through a pinion gear 13 mounted at one end of a transversely disposed shaft 14, journaled for rotation on the body and having its opposite end operated through a belt 15 driven through an engine or other suitable power plant 16 mounted toward the rear end of the body.

The pinion gear 13 is also operatively connected with a gear 17 mounted on a shaft 18 also carrying a drum 19 and about which one end of a cable 20 is wound, said cable extending over pulley wheels 21 mounted on the walking beam 10 and extending over a pulley wheel 22 mounted at the upper end of the derrick with the opposite end of the cable attached to a rope socket member 23 forming the upper section of the drilling tool.

A belt 24 is also driven from the pinion gear shaft 14 for operating a pump 25 through a countershaft and belt drive 26 and 27 respectively. The counter shaft 26 also provides a mounting for a gear wheel 28 operatively connected with a gear 29 formed at one end of a hose drum 30, said drum being journaled for rotation upon the body 5, one end of the drum having a hollow shaft 31 extending therefrom forming a connection at one end with a hose 32 wound about the drum. Within the outer end of the hollow shaft 31 extends the end of a pipe 33 forming a connection with the pump 25. A packing nut 34 is fitted between the end of the pipe 33 and the end of the shaft 31 to form a liquid tight connection between such parts.

The hose 32 extends from the drum about pulley wheels 33' mounted on the walking beam and up over a pulley wheel 34 mounted at the upper end of the derrick with the end of the hose forming a connection with a water passage 35 extending longitudinally through the body of the rope socket 23.

The rope socket 23 constitutes the upper section of the drilling tool, which also includes a double jar section indicated at 36, a drill stem 37 and drill bit 38 carried at the lower end of the tool.

The lower end of each of the drilling tool

sections is formed into an internally threaded socket member 39 with the upper end of the adjacent section formed into an externally threaded plug 40 thereby enabling a 5 threaded connection to be made between the sections. Each of the sections are provided with a bore 41 extending therethrough forming a passageway for the water fed from the hose 32 through the drilling tool to the drill 10 bit 38 mounted at the lower end thereof. The lower end of the bore 41 in each of the sections terminates in a valve chamber 42 as more clearly illustrated in Figure 6 of the drawings and within which may be fitted a jetting valve 43 having its base section ground 15 and seated upon the upper edge of the bore extending through the plug 40 and tool sections disposed immediately therebeneath. The upper portion of the valve 43 is provided 20 with a plurality of fingers 44 adapted to engage a shoulder 45 formed at the upper portion of the valve chamber to prevent the valve from closing communication with the bore 41 disposed above the valve and thus enable 25 fluid to freely pass upwardly through the bore of the drilling tool.

The lower end of the drill bit 38 is provided with a plurality of discharge passages 46 communicating with the bore 41 formed 30 in the bit, said discharge passages having their outlets through the extreme lower end of the bit.

The jar section 36 of the drilling tool is formed of a pair of longitudinally slid able 35 sections with their adjacent ends formed into links 47 inter-connected with each other. The links permit of a limited sliding movement between the sections of the jar and at the same time prevent the separation of the sections so 40 as to maintain the sections of the drilling tool for operation as a unit. The upper and lower sections of the jar are connected by a pipe section 48 having its respective ends telescopically inserted within the bore 41 of the 45 jar section and provided with a packing nut 49 to form a liquid tight connection therebetween. The pipe section 48 also has a ball and socket coupling 51 interposed therein to permit of a swivel movement between the ends 50 of the pipe 48 to compensate for a similar movement which may occur between the sections of the jar by reason of sway occurring through its link connection.

The pipe 33 communicating between the 55 pump 25 and hose 32 is fitted with a discharge pipe 50 controlled by a valve 51 and a shut off valve 52 is also interposed in the pipe 33 between said valve 51 and the pump.

In the operation of the apparatus under

normal conditions, the jetting valve 43 is removed from the drilling tool, the tool being operated through the reciprocating movement of the walking beam 10. At the same time water is forced through the tool by means of the pump 25 to facilitate the drilling operation. 60

Should an excessive supply of water be forced into the well or an inexhaustible supply be encountered during the drilling operation, the drilling tool is withdrawn and the jetting valve 43 interposed between two or more of the sections thereof in a manner as illustrated in Figure 6 of the drawing and the parts again connected and lowered in the well. 75

The cut off valve 52 leading to the pump is closed and the valve 51 opened, the supply of water in the well during the continued operation of the apparatus serving to force the borings and cuttings of the bit upwardly 80 through the drilling tool and out through the discharge pipe 50.

It is obvious that the invention is susceptible of various changes and modifications, without departing from the spirit or scope of 85 the invention or sacrificing any of its advantages, and I accordingly claim all such forms of the device to which I am entitled.

Having thus described my invention, what I claim as new is: 90

In a drilling apparatus, a sectional hollow drilling tool including a rope socket at one end and a drill bit at its opposite end, a jar section and a drilling stem section interposed between the ends of the tool, means for detachably connecting said sections, a jetting valve removably positioned at the connected ends of said sections, said drill bit having discharge ports formed therein and said rope socket having a hose connection formed thereon, a hose extending from said connection, a hose drum having a hollow shaft at one end communicating with the hose, a feed pipe for the shaft, fluid pressure means for the pipe, a pair of cut off valves interposed in said pipe, 100 one of said valves controlling communication between the hose and the fluid pressure means and said other valve controlling communication with a discharge pipe for the hose, cable supporting means for the drilling tool and 105 provided with a drum for reeling and unreeling the same, reciprocating operating means for the drilling tool and drive means for each 110 of said drums and the reciprocating operating means.

In testimony whereof I affix my signature.

JEREMIAH A. SHOWALTER.
